CASING FOR A PORTABLE ELECTRIC ICE CRUSHER OR SIMILAR ARTICLE

Joseph R. Mango, Midlothian, Ill., assignor to Adams-Pelouze Company, Evanston, Ill., a corporation

Application October 20, 1958, Serial No. 53,034

Term of patent 3½ years

(Cl. D89—1)

Fig. 1

Figure 1 is a frontal perspective view of a casing for a portable electric ice crusher or similar article, showing my new design; and

The dominant features of the design reside in the portions shown in full lines.

I claim:

The ornamental design for a casing for a portable electric ice crusher or similar article, substantially as shown and described.
